UNITED STATES PATENT OFFICE.

GEORGE MASSINGBERD TEALE, OF KINGMAN, ARIZONA.

DESIGN FOR A STATUETTE OR SIMILAR ARTICLE.

Application filed February 19, 1926. Serial No. 16,593. Term of patent 14 years.

To all whom it may concern:

Be it known that I, GEORGE M. TEALE, a citizen of the United States, residing at Kingman, in the county of Mohave and State of Arizona, have invented a new, original, and ornamental Design for a Statuette or Similar Article, of which the following is a specification, reference being had to the accompanying drawing, forming part thereof.

Figures 1 and 2 are side elevations of a statuette, or similar article, showing my new design;

Figure 3 is a top plan view of the same.

I claim:

The ornamental design for a statuette, or similar article, as shown.

In testimony that I claim the foregoing as my own, I have hereto affixed my signature.

GEORGE MASSINGBERD TEALE.
